ACOUSTIC DEVICE

Clair L. Farrand, Beverly Hills, Calif., assignor to
 United Research Corporation, Burbank, Calif.,
 a corporation of Delaware

Application August 3, 1936, Serial No. 94,072

10 Claims. (Cl. 181—31)

This invention relates to loud speakers.

It is well known in the art to allocate a part of the acoustic range of a sound reproducing apparatus to one type of loud speaker and another part or parts to another type (or other types) of loud speaker.

This invention relates to the type of loud speaker useful in a so-called two-way system, wherein the acoustic range is handled by only two types of loud speakers, the type of loud speaker of the present invention being particularly adapted to reproduce acoustic frequencies from about three hundred cycles to the upper limit, i. e., eight thousand cycles or higher.

15 The objects of the present invention comprise an efficient reproduction of sound waves over a wide frequency range, with large power, and while attaining a substantially uniform distribution of the sound waves, particularly of the higher 20 frequencies which have a tendency to remain in a narrow beam.

The novel features of one embodiment of the invention will be described in the accompanying specification, and particularized in the appended 25 claims in connection with the accompanying drawings, wherein;

Fig. 1 is a sectional elevational view of a loud speaker embodying the present invention.

Fig. 2 is an enlarged fragmentary sectional 30 view of the annular diaphragm and the accompanying sound chamber forming parts.

Fig. 3 is a front view looking toward the mouth portions of the nested horn assembly.

Fig. 4 is a plan sectional view through the 35 throat block and is taken along the line 4—4 of Fig. 1.

Fig. 5 is a sectional plan view through the lower set of diaphragm clamping rings and is taken along the line 5—5 of Fig. 1.

40 Fig. 6 is a bottom plan view of a portion of the annular diaphragm showing the connection of the voice coil thereto.

Referring now to Figs. 1 and 5, the driving unit 1 of the loud speaker comprises a U shaped magnetic frame 2, having a central core 3 of magnetic material secured thereto. A circular plate 4, comprising an inner pole piece, is provided on the upper surface of the core 3, and this assembly, including the frame 2, core 3, and pole piece 4, is secured together by means of a bolt 5. An annular plate 6, comprising an outer pole piece, is secured to the magnetic frame 2 by means of bolts 7, with its inner edge concentric with and closely adjacent to the outer edge of the inner pole piece 4. An electro-magnetic coil 9

is provided around the core 3, and receives a supply of direct current so as to produce a constant magnetic flux between the two separated pole pieces 4 and 6.

As will be noted in Fig. 2, the adjacent outer and inner edges of the pole pieces, 4 and 6, respectively, are undercut as at 10, leaving only a short length of parallel, closely adjacent, pole faces at 11. The space thus provided between the parallel faces 11 of the pole pieces 4 and 6, 10 accommodates the voice or driving coil 12 of an annular diaphragm 13. The diaphragm 13 is supported below its inner and outer edges by means of inner and outer concentric supporting rings 14 and 14¹, respectively. Upper concentric 15 clamping rings 15 and 16 clamp the edges of the diaphragm upon the supporting rings 14 and 14¹ by means of bolts 17.

A frusto-conical member 18, with a co-extensive conical member 19, secured together and to 20 the upper surface of the inner clamping ring 15 by means of bolts 20 and the central bolt 5, and a casing member 21, all concentric with the dia- 25 phragm 13, form an annular sound passage 22 leading to the central portion of the annular 25 diaphragm 13.

The annular sound passage 22, at the tip of the conical member 19, communicates with a tubular passage 23 formed in an adapter 24. This passage 23 is co-extensive with a similar passage 25 30 formed in a throat block 26.

Adapter 24 is fitted in a counter-bored portion on the top of the casing member 21, and has an annular shoulder portion 24¹, which is engaged by a locking nut 27 threadably secured to the cas- 35 ing member 21. The throat block 26 is threadably secured at 26¹ to the upper portion of adapter 24. The upper portion of the throat block 26 is formed in a funnel shape having diverging flanges 28, so as to receive the throat 40 portions of a plurality of horn sections 29 to 44, inclusive. A suitable cement 54 is provided to secure the throat portions of the various horns together between the flanges 28 of the throat block 26. These various horns are all identical 45 in shape and size, having their longitudinal axes diverging from each other away from their throat portions. This arrangement of nested horn sec- 50 tions eliminates the well known directional or beam effect of the higher frequencies by means of the approximate spherical surface formed by the combined mouth opening 45 thereof. That is, in the case of a spherical source of sound, such as a diaphragm in the shape of a sphere, the sur- 55 face of which vibrates radially in accordance

with the frequency and amplitude at every point thereon, sound would be radiated through the entire frequency range, including the higher frequencies, in all directions. In case, however, the source from which the sound is radiated constitutes only a segmental portion of a sphere, this uniform sound radiation would still prevail through the solid angle subtending the segmental surfaces and the center of curvature thereof. This condition is approximated by the nested horn assembly 29 to 44, inclusive, by angularly disposing the longitudinal axes thereof so as to form at their combined mouth opening a spherical segment from which the sound is radiated into the atmosphere. It will thus be seen that the individual sound waves propagated in the various horns will have exactly the same characteristics and will be so timed that they will unite at the combined mouth opening to form a spherical wave front. The combined throat opening 46 of the various horns 29 to 44, inclusive, is also in the shape of a spherical segment. Preferably, the height of the segmental surface thus formed, as indicated by the dimension "A", between the single throat opening of the center horn 43 and the chordal line passing through the throat portions of the outer horns 29 and 35 (Fig. 1) is of the order of one-quarter wavelength of the highest frequency sound to be reproduced so as to prevent distortion and/or cancellation of a nearly planar wave front on entering the combined throat opening 46 and emerging from the combined mouth opening 45. It will be seen, therefore, that since all of the horns are of the same length, intersection "B" of the longitudinal axes of the horns also forms the center of curvature for both the combined throat openings 46 and the combined mouth openings 45.

As will be seen in Fig. 3, the combined throat portion as indicated by the dotted line 46¹ is rectangular in shape and opens into the sound passage 25 of the throat block 26, which is of the same rectangular shape and size in cross-section at its upper end (Fig. 4). The passage 25 and the co-extensive passage 23 in the adapter 24 gradually change in cross-sectional shape until they assume a substantially circular cross-section adjacent the tip of the plug 16.

Preferably, the annular passage 22, tubular passages 23 and 25, and the passages forming the various individual horns 29 to 44, inclusive, have an exponential rate of taper or exponential rate of cross-sectional increase along the lengths thereof, increasing from the throat to the mouth portions thereof, this rate being the same throughout. The size of these various passages is determined by the upper and lower frequency limits. For example, the size of the throat opening of the annular passage 22, adjacent the diaphragm 13, is determined by the amount of air velocity change between the diaphragm chamber and the annular passage 22. The limiting factor in making the throat of passage 22 as small as possible is the frictional resistance of the air with the walls of passage 22 when moving at the increased velocity and the harmonic distortion which results when the instantaneous pressures depart too far from atmospheric pressure. The number of horns is determined by the solid angle through which the sound, particularly of the higher frequencies, is to be distributed. In the present case (Fig. 3), the horns are arranged in five vertical rows with three horns in each row. This particular arrangement of horns, however, may be varied to suit the conditions of the par-

ticular auditorium or theatre in which the loud speaker is to be placed. The length and rate of taper of the various horns is determined by the lowest frequency sound to be reproduced and are preferably such that the smallest dimension of the combined mouth opening of the various horns is on the order of one-half of the wavelength of the lowest frequency to be radiated.

Referring to Fig. 2 it will be noted that the annular diaphragm 13, which in the present case is constructed of Duralumin on the order of .002 inch in thickness, comprises, in radial cross-section, an annular trough 46, with relatively smaller annular corrugations 47 and 48 on either side thereof. These corrugations 47 and 48 increase the flexibility at the edge to allow the annular trough portion 46 to be reciprocated as a rigid section by the voice coil 12. The sound chamber or sound box 49, as defined by the upper surface of the diaphragm 13 and the lower surfaces of the ring 16 and member 18, closely follows the contour of the cross-sectional shape of diaphragm 13. That is, the under surfaces of the ring 16 and member 18, directly above the active portion of diaphragm 13, are similar in shape to the cross-sectional form of the annular trough 46 and corrugations 47 and 48. However, the curvature of the bottom surfaces of the ring 16 and member 18, directly opposite the trough portion 46, and which extend thereinto, is slightly less than that of this trough portion.

The distance from the annular throat opening 55 of the annular passage 22 to the inner and outer edges of the diaphragm sound chamber 49, or in other words, to the supported edges of the diaphragm 13, is of the order of one quarter wavelength of the highest frequency sound intended to be reproduced. In the present case, the dimension is about 0.4 inch. Thus, there will be no undue cancellation of a sound wave of 8000 cycles generated in the chamber 49 due to the difference between the time required for a wave originating at the extreme inner or outer edge of the diaphragm 13 to enter the sound opening 55 and the time required for a corresponding wave generated at the central portion of the trough 46 of diaphragm 13 to enter the same sound opening 55. If, for example, this distance between the supported edges of diaphragm 13 and the opening 55 were as great as one-half the wavelength of the highest frequency sound intended to be reproduced, a wave originating at the furthermost point in the chamber 49 would be 180° out of phase with a wave originating at a point directly opposite the opening 55 and therefore the two waves would cancel each other.

Referring to Figs. 2 and 6, the voice coil 12 is secured to the central portion of the annular trough 46, directly below the annular sound passage 22. This construction allows the driving force, i. e., the coil 12, to be directly in the center of the plunger portion, i. e., the trough 46 of diaphragm 13, and also directly in line with the exit of sound through the passage 22. As will be noted in Figs. 2 and 6, the driving or voice coil 12 is secured to the central portion of diaphragm 13 by means of a cylindrical support 56 of cardboard or the like material around which coil 12 is wound. One edge of the support 56 is serrated with alternate serrations 57 and 58, etc., extending on the same side, horizontally, to form a base which may be cemented or otherwise secured to the under surface of the annular trough portion 46.

Vents 59 (Figs. 2 and 5) in the form of a plu- 75

rality of holes arranged in a concentric path about the diaphragm 13 are provided in the inner pole piece 4 to communicate the inner back chamber 60, formed between the back surface of diaphragm 13, pole piece 4 and ring 14, with the outer atmosphere. A second series of vents in the form of radial slots 61, provided in the dia-
5 phragm supporting ring 14¹, communicate the outer back chamber 62, formed by the back sur-
10 face of diaphragm 13, outer pole piece 6 and ring 14¹, with the outer atmosphere. These two series of vents thus assist the very narrow spaces be-
15 tween the voice coil 12 and the adjacent inner and outer edges 11 of the pole pieces 6 and 4,
respectively, in relieving the damping effect on the diaphragm due to the practically enclosed back chambers 60 and 62.

I claim:

1. An acoustic device comprising an annular diaphragm having a single annular trough there-
20 in, a housing forming a sound box for said dia-
phragm, said sound box having a sound exit opening therein at the center of and within the trough portion of said diaphragm, and means at-
25 tached to the convex side of said trough for actu-
ating said diaphragm.

2. An acoustic device in accordance with claim 1 in which said last mentioned means comprises a driving coil connected to said diaphragm di-
30 rectly opposite said sound exit opening in said housing.

3. An acoustic device in accordance with claim 1 in which said housing forming said sound box has a convex portion thereof extending into said 35 sound box and into the concave trough portion of said diaphragm and conforming to the outline of said trough.

4. An acoustic device comprising a sound pro-
40 ducing unit having an annular diaphragm, flex-
ible corrugations at the edges thereof, a casing forming a sound box for supporting the edges of said diaphragm, said sound box having a sound exit opening therein, a common throat portion for said sound box, a plurality of horns connected to said throat portion, the inlets of said horns being arranged along an arc concentric with the 45 arc along which the outlets of said horns are arranged, the distance from the chord connecting

the inlets of the outside horns, to the inlets of the center horns, and the distance from the edges of the annular diaphragm to the sound exit opening of said sound box portion being of the order of one-quarter wavelength of the highest frequency to be produced, and means for driving said diaphragm.

5. An acoustic device in accordance with claim 4 in which the back of said diaphragm is connected with the open air through a plurality of 10

6. An acoustic device in accordance with claim 4 in which said last mentioned means comprises a voice coil attached to the center of the convex side of said diaphragm, said attachment comprising a serrated medium uniformly distributed on said diaphragm about the line of attachment to said coil.

7. A sound reproducer comprising an annular diaphragm having a central annular curved trough body portion, a casing forming a sound box for said diaphragm, and means for mounting said diaphragm, said body portion being supported by said mounting means by flexible integral inner and outer circumferential corrugated 20 portions concentric with said diaphragm.

8. A sound reproducer in accordance with claim 7 wherein the corrugations of said corrugated portions are small in comparison with said curved trough body portion.

9. A sound reproducer in accordance with claim 7 in which said sound box casing has a convex portion thereof extending into and conforming to the curvature of the annular curved trough body portion of said diaphragm and also con- 35 forming to the curvature of said corrugated por-
tions.

10. An acoustic device comprising an annular diaphragm having a central annular curved trough portion with corrugated flexible inner and outer portions, a casing forming a sound box surrounding said diaphragm, said casing having a convex portion thereof extending into and conforming to the trough body portion of said dia-
phragm, and a driving coil mounted along the 40 central portion and on the convex side of the trough body portion of said diaphragm.

CLAIR L. FARRAND.
